UNITED STATES PATENT OFFICE.

JILES S. SHOCKLEY, OF NASHVILLE, TENNESSEE, ASSIGNOR TO THE SHOCKLEY MOTOR COMPANY, OF NASHVILLE, TENNESSEE, A CORPORATION OF DELAWARE.

PUMP.

1,379,785.

Specification of Letters Patent. Patented May 31, 1921.

Application filed September 16, 1918. Serial No. 254,336.

To all whom it may concern:

Be it known that I, JILES S. SHOCKLEY, a citizen of the United States, residing at Nashville, in the county of Davidson and State of Tennessee, have invented a certain new and useful Improvement in Pumps, of which the following is a full, clear, and exact description, reference being had to the accompanying drawings.

10 This invention relates to improvements in pumps of the rotary type, and has for its object the production of a very durable, smooth running pump of extremely high efficiency; wherein the working parts are 15 easily accessible, and operate with a minimum degree of friction; and wherein, by the use of suitable joints and packing elements, leakage is effectually prevented.

A further object comprehended by my 20 invention is the production of a pump of the foregoing nature through which hard substances, such as gravel, slugs and the like may be circulated without injuring the pump or interfering with its operation.

25 And again, more generally, it is an object of my invention to provide a simple construction through which the foregoing objects are attained.

To these ends my invention may be defined as consisting of the combinations of 30 elements set forth in the claims annexed hereto and illustrated in the drawings accompanying and forming a part hereof and wherein Figure 1 is a sectional front elevation of my improved pump; Fig. 2 is a sectional end elevation, the plane of section being indicated by either of the two section lines 2-2 of Fig. 1; Figs. 3, 4, and 5 are sectional details on the respective correspondingly numbered lines of Fig. 2; Fig. 6 40 shows, in perspective, parts of the valve element in separated condition; and Fig. 7 is a horizontal section through the base on line 7-7 of Fig. 1.

45 In its present embodiment, my invention is incorporated in what may be termed a twin pump comprising generally a base 1, pump casings 2 and 3 which are mounted upon ends of the base, and a driving element, herein shown as a pulley, is situated between the pump casings for operating the pumps.

The base 1 consists of a hollow casting divided by a longitudinal partition 6 into

an inlet compartment 7 and an outlet compartment 8. A supply pipe 9 is shown as having communicative connection with the central portion of the inlet compartment 7, and an exhaust pipe 10 has similar connection with the outlet compartment at a point 55 opposite the pipe 9. It will be observed that the ends of the base turn upward and that the upper face of each end is smoothed off to form a supporting surface for one of the pump casings. Each of the compartments 7 and 8 opens through circular apertures formed in these surfaces, and each aperture is surrounded by a depressed seat 12.

The pumps proper, comprising the casings 2 and 3, are identical, so that a detail description of one will suffice for both.

Referring to the pump situated on the left hand end of the base, as the apparatus is viewed in Fig. 1, the casing 2 contains a 75 cylindrical chamber 15 that is closed on one side by a face plate 16, and on the other, by a plate 17. Below the chamber 15, the casing contains inlet and outlet passageways 18 and 19 which open through its bottom 80 wall into the chamber and which also communicate with the compartments 7 and 8 of the base 1, the passageways being separated by a transverse partition wall 20 which registers with the partition 6 of the 85 base. It will be noted, upon referring to Fig. 2, that a depressed seat 21 surrounds the lower ends of the passageways 18 and 19 and, with the previously mentioned depressed seats of the base, constitute annular 90 confining recesses for the packing rings or gaskets 22 of lead or other compressible material, the casing and base being clamped firmly together by screws 23 or their equivalents. Because of the confinement of the 95 gaskets 22, there is no danger of their being blown out by the high pressure generated within the pump.

A pivot pin 25 is supported at its middle within a lug 26 that extends inward from the outer wall of the passageway 18, the lug being situated at the transverse center of the passageway so that the ends of the pin are exposed. A valve element 28 is journaled upon the pivot pin 25 and comprises 100 halves 29 and 30, shown in detail in Fig. 6. Each half of the valve element has an arm 31 that terminates at one end in a cylindri-

cal boss 32 that is journaled upon one end of the pin 25, and preferably an anti-friction bearing, indicated at 32^a, is interposed between the pin and boss. The opposite 5 ends of the arms 31 carry sections of a fin 33 which has its outer face curved on an arc described from the center of the pin; and the surface of the wall 20 across which the fin is designed to move when the valve 10 element is oscillated, is shown similarly curved. Perfect freedom of movement of the valve element requires that the adjacent surfaces of the wall and fin be slightly spaced apart, and to prevent leakage between 15 the surfaces I employ a packing consisting of a bar 35, contained within a groove 36 in the wall 20 and urged into contact with the face of the fin by a leaf spring 37 that is interposed between the back of 20 the bar and the opposed wall of the groove. The two sections or the halves of the valve element are secured together by a screw 38 which passes freely through bores in one of the halves and is threaded into the other, 25 a dowel pin 39, which occupies registering recesses in the two halves, assisting in holding them in proper fixed relation to each other. While the passageways 18 and 19 open through the sides of the casing 2, it 30 will be observed that they are of less width than the casing where they open into the chamber 15, leaving the edge portions of the cylindrical wall of the chamber unbroken at its lower side except at the point where the 35 fin 33 enters the chamber. To retain the reduced sections of the chamber wall on each side of the opening of the passageway 18 in proper position, I connect the free ends of such reduced portions to the face 40 plates 16 and 17 by dowel pins 40, or their equivalents. My reason for retaining the cylindrical wall of the chamber 15 unbroken so far as possible will presently become apparent. The valve element 31 is elevated 45 to project its fin 33 into the chamber 15 by means which I shall now describe. Substantially coincident with the vertical center of the inlet passageway 18 is an internally threaded hollow boss 42 in the base. Into 50 this is screwed the upper end of a cup 43 which contains a helical spring 44. A head 45 fits into the upper end of the spring and is guided within the cup and has a flange 46 that rests upon the spring. A rod 47 rises 55 from the head 45 and its upper end is forked to receive a beam 48, the ends of which bear upon the arms 31 of the valve element. It is clear, therefore, that the spring 44 constantly tends to elevate the valve element 60 and projects its fin 33 into the chamber 15. The beam 48 is held against withdrawal from the forked end of the rod 47 as by a cotter pin 49 that extends through the branch of the fork above the beam; and the 65 lower edge of the beam may be notched

to embrace the crotch of the fork to hold the beam against longitudinal displacement. It will be apparent upon reflection that the beam 48 serves as an equalizer to distribute the force of the spring 44 evenly between 70 the two ends of the valve element.

The inner face plate 17 of each of the casings 2 and 3 has a central boss 50, containing an anti-friction bearing 51 within which a shaft 52 is journaled, a suitable stuffing 75 box effectually closing the outer end of the boss 50 so as to prevent leakage about the shaft. At its end adjacent the chamber 15, the shaft 52 is provided with a disk 55 which carries a crank pin 56, offset a suitable distance from the shaft 52 and extending to within a slight distance of the outer face plate 16. The hub 57 of a rotor or piston 58 is journaled, through suitable anti-friction bearings 59, upon the crank pin 56, 80 and a transverse line of its periphery is constantly in contact with a portion of the cylindrical wall of the chamber 15. The piston 58 has a working fit between the opposed face plates. 90

The adjacent ends of the opposed pump shafts 52 are coupled together by a connection consisting of a sleeve 60 having transverse key slots that register with key slots in the shaft sections and designed to receive wedge keys 61 that are driven through the sleeve and shaft sections and tend to draw the shaft sections toward each other. The hub of the pulley 4 may be secured by any suitable means to the coupling or 100 sleeve 60.

The method of assembling and disassembling the apparatus will be clear to those skilled in the art, although it may be stated that to remove the pump shafts, the pulley, 105 which is split, may have its halves separated, and removed from the sleeve so that the keys 61 may be dislodged. The outer face plates 16 of the pump casings may be removed, and a pointed instrument inserted 110 through the aperture 64 of the sleeve or coupling 60 between the ends of the shafts 52 to start them, when they may be withdrawn endwise through the pump casings.

In the operation of the apparatus, the 115 pulley is driven by suitable means to rotate the shafts 52 in the direction indicated by the arrow in Fig. 2. This results in each piston 58 being moved about in rolling contact with the cylindrical wall of the chamber 15. As it travels up the right hand side of the chamber, as viewed in Fig. 2, it starts to suck in a quantity of fluid through the passageway 18, the receiving chamber, or that to the right hand side of the fin 33, 120 growing gradually larger as the piston is advanced in the direction of the arrow, and the suction is continued until the point of contact between the piston and the chamber wall reaches the exhaust passageway 19, it 125 130

being understood that the fin 33 ascends and descends with the action of the piston while bearing constantly thereagainst. Just as soon as the point of contact between the 5 piston and chamber wall moves again to the right of the fin, the pump starts to inhale a fresh supply of fluid while that previously drawn in is being forced about the chamber and through the exhaust passage- 10 way 19.

I have previously stated that solid particles, such as gravel or slugs, could be circulated through the pump without injuring it or interfering with its operation. This 15 is due to that fact that such particles tend to follow the point of contact between piston and cylinder rather than to fall back and travel just in advance of such point, because the velocity of the fluid tends to 20 throw such particles forward and the centrifugal action maintains them adjacent the cylindrical wall where the velocity of the fluid is naturally the highest.

By leaving extensions of the chamber 25 wall on each side of the inlet and outlet passageways 18 and 19 the piston is provided with a continuous track or supporting surface so that, even when running at a high rate of speed, it has no tendency to 30 drop into the passageways but will run smoothly over the parts without the slightest knock.

Having thus described my invention, what I claim is:—

35 1. In a pump of the character set forth, the combination of a casing having a cylindrical chamber, a cylindrical piston of lesser diameter than the chamber and situated therein, means for impelling the piston 40 about the chamber in contact with the cylindrical wall thereof, the chamber having an inlet and an outlet port, a valve element pivoted exteriorly of the chamber and having a fin projecting through the cylindrical 45 wall of the chamber between said ports, and bearing upon the cylindrical face of the piston throughout the breadth thereof, a rod, an equalizer interposed between said rod and the valve element, and a compression spring supported within the casing and 50 tending to force the rod in a direction to engage the fin of the valve element with the periphery of the piston.

2. In a pump of the character set forth 55 the combination of a casing having a cylindrical chamber, a cylindrical piston of lesser diameter than the chamber and situated therein, means for impelling the piston about the chamber in contact with the cylindrical wall thereof, the chamber having an inlet and an outlet port, a valve element pivoted exteriorly of the chamber and having a fin projecting through the cylindrical wall 60 of the chamber between said ports, said 65 valve element having spaced parts, a bar

having its ends bearing against said parts, a rod having a forked end loosely embracing the central portion of the bar, and a compression spring supported within the casing and tending to force the rod in a direction 70 to engage the fin with the periphery of the piston.

3. In a pump of the character set forth, the combination of a casing having a cylindrical chamber, a cylindrical piston of lesser 75 diameter than the chamber and situated therein, means for impelling the piston about the chamber in contact with the cylindrical wall thereof, the chamber having an inlet and an outlet port, a pivot pin supported at its middle by the casing exteriorly of the chamber, a valve element comprising opposed parts adjustable toward and from each other and having each a hub that is journaled upon one end of the pivot pin, 80 means for securing the parts of the valve element together, said element including a fin projecting through the cylindrical wall of the chamber, and means acting to move the valve element in a direction to engage 85 its fin with the periphery of the piston.

4. In an apparatus of the character set forth, the combination of a base containing an inlet compartment and an outlet compartment, the ends of the base having surfaces through which the aforesaid compartments open, a pump casing surmounting each end of the base and having surfaces contacting with the aforesaid surfaces of the base, the casing having apertures registering with the openings in the base, pumping mechanism within each casing and involving a shaft projecting therefrom toward the other casing, a coupling element connecting said shafts, and a driving element mounted upon the coupling element. 100

5. In apparatus of the character set forth, the combination of a base containing an inlet compartment and an outlet compartment, the ends of the base having surfaces 105 through which the aforesaid compartments open, a pump casing surmounting each end of the base and having surfaces contacting with the aforesaid surfaces of the base, each casing having apertures registering with the openings in the base, pumping mechanism within each casing and involving a shaft projecting therefrom toward the other casing, means connecting said shafts, and a driving element attached to the shafts between the casings. 110

6. In apparatus of the character set forth, the combination of a base having at its ends supporting surfaces the base containing inlet and outlet compartments opening 115 through said surfaces, a pump casing surmounting each surface and having passageways communicating with the compartments of the base, the pump casings having cylindrical chambers that are substantially 120 125 130

in axial alinement and into which said passageways open, the ends of each casing being open, face plates closing the outer ends of the casing, face plates closing the inner 5 or adjacent ends of the casing and having bearings therein, shafts journaled within said bearings and concentric with the cylindrical chambers, crank pins carried by the shafts and projecting into the chambers, 10 cylindrical pistons journaled upon the crank pins and arranged to traverse the cylindrical walls of the chambers when the shafts are rotated, a fin projecting through the cylindrical wall of each chamber between 15 the aforesaid passageways, means urging the fins into contact with the peripheries of

the pistons, and a driving element applied to the inner ends of the shafts.

7. In apparatus of the character set forth, the combination of a base, pumps mounted 20 upon the base in spaced relation to each other, the operating shafts of the pumps approaching each other in axial alinement, a coupler assembly connecting the ends of the opposed shafts, and driving means 25 mounted upon the coupler and serving to maintain the coupler in assembled condition.

In testimony whereof, I hereunto affix my signature.

JILES S. SHOCKLEY.
